Primary Examiner — David G Muller*Assistant Examiner* — Nathan M Johnston(74) *Attorney, Agent, or Firm* — Mark Malek; Widerman Malek, PL(57) **CLAIM**

The ornamental design for a plant pot holder, as shown and described.

DESCRIPTION

FIG. 1 is a front perspective view of a plant pot holder showing my new design.

FIG. 2 is a rear perspective view thereof.

FIG. 3 is a front view thereof.

FIG. 4 is a side elevation view thereof.

FIG. 5 is another side elevation view thereof.

FIG. 6 is a top plan view thereof.

FIG. 7 is a bottom plan view of thereof.

FIG. 8 is a top perspective view thereof looking from the top.

FIG. 9 is a front view thereof; and,

FIG. 10 is a front perspective environmental view thereof. The broken lines illustrate a lower stake portion, indicia, and a design on a handle portion that form no part of the claimed invention.
